UNITED STATES PATENT OFFICE.

ALBERT B. STROCK, OF OAKLAND, CALIFORNIA.

TELEPHONE ATTACHMENT.

1,263,481.

Specification of Letters Patent. Patented Apr. 23, 1918.

Application filed December 7, 1915. Serial No. 65,532.

To all whom it may concern:

Be it known that I, ALBERT B. STROCK, a citizen of the United States, residing at Oakland, in the county of Alameda and State of California, have invented certain new and useful Improvements in Telephone Attachments; and I do hereby declare the following to be a full, clear, and exact description of the invention, such as will enable others skilled in the art to which it appertains to make and use the same.

This invention relates to an attachment for a telephone, and has for its primary object to provide a simple and efficient device for movably and adjustably supporting the receiver in position adjacent the ear of a person using a telephone.

Another object is the provision of a receiver supporting device for telephones embodying means whereby the receiver supporting hook of the telephone is automatically actuated by swinging the main supporting arm of the attachment inwardly.

With these and other objects in view, the invention consists in the novel construction, combination and arrangement of parts as will be hereinafter specifically described, claimed and illustrated in the accompanying drawing, in which:

Figure 1 represents a front elevation of the improved attachment, partly in section, Fig. 2 represents a side elevation thereof, and

Fig. 3 represents a top plan view of the telephone and attachment.

Referring to the drawing in detail, where-in similar reference numerals designate corresponding parts throughout the several views, the numeral 5 indicates generally a telephone of a well known type embodying the supporting standard or post 6, base 7, transmitting instrument 8 and receiver hook 9 pivotally secured to the standard 6 and adapted to support the receiver 10.

The improved receiver-supporting device includes an attaching band 12 engaged with the standard 6 and secured in position thereon by a bolt 13. The free terminals of the band 12 are extended in parallel relation, as indicated at 14, and receive a pivot pin or bolt 15 pivotally securing the main supporting arm of the attachment, designated generally by the numeral 16, in the plane of the axis of the pivotal movement of the receiver hook 9.

The upper extremity of the main support-

ing arm 16 is directed forwardly in a horizontal plane, as indicated at 17, and is pivotally connected with an angular coupling member 19 by a pivot pin or bolt 20. The opposite terminal of the angular member 19 is pivotally secured between the parallel terminals of a receiver-engaging band 21 by a pivot pin or bolt 22.

The portion of the main supporting arm 16 below the attaching band 12 is formed with a crimp 23 adapted to engage the standard 6, during outward movement of the upper extremity of the supporting arm, to limit the movement thereof.

As clearly illustrated in Fig. 1, the band 12 is so positioned upon the standard 6 as to dispose the spaced parallel ends 14 there-of below the receiver hook 9, and the portion of the supporting arm 16 directly above the receiver arm is curved or crimped inwardly to define a substantially U-shaped hook-engaging and depressing member 24.

When it is desired to use the telephone the upper extremity of the supporting arm 16 is swung outwardly and the receiver 10 adjusted in proper position with relation to the user's ear. The outward movement of the upper extremity of the arm 16 is limited by the stop member 23 and during the outward movement thereof the receiver hook-engaging member 24 is disengaged from the inner extremity of the receiver hook 9, thus permitting the latter to move upwardly under the influence of the usual actuating spring provided therefor. Subsequent to using the telephone, the arm 16 is tilted inwardly to the full line position illustrated in Fig. 1, the member 24 engaging the upper surface of the hook 9 and depressing the latter, thus breaking the electrical circuit to the telephone.

What I claim is:

1. In combination, a telephone including a pivoted receiver hook, and an attachment, said attachment including an attaching band fastened to the telephone beneath the pivoted receiver hook, a supporting arm pivotally secured to said attaching band and movable on an axis parallel with the axis of the pivoted receiver hook, the upper terminal of said arm being directed forwardly of the telephone, a stop member carried by said arm and arranged under the receiver hook for limiting the outward swinging movement of the upper forwardly extending end of the arm, a U-shaped member formed in

said arm above the pivoted receiver hook for engaging and depressing the latter during the inward movement of the supporting arm, an angular coupling member pivotally secured to the upper extremity of said arm, and means carried by said coupling member for supporting the telephone receiver.

2. The combination with a telephone stand having an upright body and a pivoted switch lever, of an adjustable bracket adapted to be clamped to the body part of the stand, an arm pivotally mounted in said bracket, a clamp member having a swivel connection with the upper end of the arm and adapted to embrace and support the

telephone receiver, a cam on the arm engageable with the switch lever and adapted to release or depress the same synchronously with the movements of the receiver carrier, and an extension of the carrier below the 20 fulcrum adapted to close against the body and serve as a stop to retain the receiver in position for use.

In testimony whereof I affix my signature in presence of two witnesses.

ALBERT B. STROCK.
